UNITED STATES PATENT OFFICE.

JACOB W. RIGLANDER, OF NEW YORK, N. Y.

WATCH-KEY.

SPECIFICATION forming part of Letters Patent No. 630,562, dated August 8, 1899.

Application filed March 11, 1899. Serial No. 708,780. (No model.)

To all whom it may concern:

Be it known that I, JACOB W. RIGLANDER, a citizen of the United States, residing in the city, county, and State of New York, have 5 made certain new and useful Improvements in Watchmakers' Tools, of which the following is a specification.

My invention has special relation to tools employed by watch makers and repairers to 10 operate on certain parts of the watch mechanism to detach or attach the same, especially certain sleeves connected with the winding mechanism; but it may also be used for other purposes. Prior to my invention it has 15 been customary to make these sleeve-keys, of which it is required that a number of differing engaging tools or projections to conform to the structure of the sleeve of each particular watch manufacturer be made, and to af- 20 fix each of them permanently to a separate handle or to provide a handle which would detachably receive the keys, the keys in the latter case being made double ended—that is, provided with engaging surfaces or projec- 25 tions at both its ends, one of the ends being slipped into the tool—and in another case it has been customary to provide a disk in which a group of the separate keys are inserted and permanently fixed therein.

My invention has for its object to improve 30 upon this latter construction, and in conformity therewith I employ a disk so constructed as to detachably receive each of the keys, so that not only is the construction of the tool 35 greatly expedited, but by the detachment of one of the keys from the disk or holder in the event of the breakage of its operative end or projections a new one can be readily substituted, thus avoiding the destruction of the 40 entire tool by the fracture of one of the keys, or avoiding the necessity of employing skilled machine workmen to remove the broken key and substitute a new one.

A further feature of my improvements re- 45 sides in the fact that new keys or keys adapt- ed to be employed in connection with a new form of sleeve can be substituted for the one or ones in my improved tool without necessi- tating the disuse of the entire tool or the mul- 50 tiplying of the tools.

My invention, therefore, resides in the construction and combination of parts herein-

after described, and further pointed out in the claims.

In the drawings forming part of this speci- 55 fication, Figure 1 is a front elevation of a complete tool made in accordance with my invention, partly in section; Fig. 2, a transverse sectional elevation of the holder on the line x x , Fig. 1; Fig. 3, a longitudinal sectional 60 elevation of the holder approximately on the line y y , Fig. 4; Fig. 4, a plan or edge view of the disk or holder; and Fig. 5 shows, respectively, a side and end elevation of one of the 65 keys improved in accordance with my invention.

Similar numerals of reference indicate corresponding parts throughout the several views.

The tool, which may be of any desired size, 70 comprises, preferably, a circular or disk shaped body or holder 1, preferably cast into the desired shape and having a central aperture 2, if desired, the periphery of the holder being provided with a series of radially-ex- 75 tending cylindrical holes 3.

Preferably for convenience of manipulation the body of the holder is reduced in diameter intermediate of its periphery, which reduction in diameter is formed by the down- 80 wardly-extending annular flanges 4, which form an annular groove 5, rectangular in cross-section and of smaller diameter than the diameter of the holes 3, so as to form slightly- 85 rounded shoulders 6, (more clearly seen in Fig. 4,) the holes 3 opening into the groove 5.

It is not essential to my invention that the body or holder be cast, as it can be made of sheet metal and either drop-forged or spun into shape, according to which is found most 90 economical; but I prefer to cast the body on account of the strength which results in the structure consistent with lightness.

At Fig. 5 is shown the sleeve-key, which 95 comprises a stem 7, on which the key 8 is formed, of the desired shape or configuration and having a suitable number of projecting prongs and a shank 9, which is circular in cross-section and which is provided at its end with a projecting tongue 10 of a shape in 100 cross-section corresponding with that of the groove 5, the ends of the tongue partaking of the exterior configuration of the shank, so as to avoid the necessity of a special configura-

tion of the tongue. The shank 9 of the key is preferably of such a diameter that it will snugly fit the hole 3, so as to prevent vibration of the key in the holder, while at the same time the tongue fitting snugly in the coöperating parts of the groove 5 prevents the key from turning in the holder, the shoulders 11 of the shank resting on the shoulders 6 of the holder.

- 10 The fitting of the shank of the key to the holder should preferably be so tight as to require considerable force to withdraw it, which, however, can be readily accomplished either with the finger or a plier. This snug fitting yet readiness of detachability or insertion of the key in the holder, combined with means for preventing the rotation of the key while in use, I consider a very valuable portion of my invention.
- 15 It is apparent that the illustrated embodiment of my invention may be modified in various ways, among which the holder need not be of the shape shown herein and may be otherwise conformed. It is not essential that 20 the groove be continuous as a locking-aperture, for the tongue of the key may be otherwise provided without making the groove continuous. Neither do I limit myself to making the shank of the key cylindrical in cross-section, as it may be plural sided without departing from the spirit of my invention, and, further, I do not limit myself to the particular kind of key used in connection with my tool, as watch-keys, gage-keys, or any other 25 suitable key or tool can be used in connection with the construction shown and described herein.
- 30 The tongue, in addition to preventing the rotation of the key in the holder, provides 35 means for giving the projections from the end

of the key their proper disposition in relation to the holder, which is very often desired for the purpose of enabling an expeditious engagement of the key with the appropriate part of the watch in conformity with the position of the hand of the user of the tool. 45

Having described my invention, I claim—

1. In an article of the class described, the combination with the holder provided with the interior annular groove of angular cross-section, a series of radially-disposed circular holes extending to the groove out from the periphery of the holder, the groove being of less diameter than that of the holes whereby shoulders are formed at the bottom of the 50 holes and a series of keys having cylindrical shanks to fit the holes, shoulders to fit the shoulders in the holder and projecting tongues to engage the opposing walls of the groove, substantially as described. 55

2. In an article of the class described, the combination with the holder provided with a central transverse aperture and an interior annular groove leading into said aperture, a series of radially-disposed holes extending 60 from the groove out to the periphery of the holder, the grooves being of less diameter than that of the holes whereby shoulders are formed at the bottom of the holes, and a series of keys having cylindrical shanks to fit 65 the holes, shoulders to fit the shoulder in the holder, and projecting tongues to engage the opposing walls of the groove, substantially as described. 70

Signed at the city, county, and State of New York this 6th day of March, 1899.

JACOB W. RIGLANDER.

Corrections in Letters Patent No. 630,562.

It is hereby certified that in Letters Patent No. 630,562, granted August 8, 1899, upon the application of Jacob W. Riglander, of New York, N. Y., for an improvement in "Watch-Keys," errors appear in the printed specification requiring correction, as follows: On page 2, line 52, the word "to" should read *from*, and same page and line, the word "from" should read *to*; and that the said Letters Patent should be read with these corrections therein that the same may conform to the record of the case in the Patent Office.

Signed, countersigned, and sealed this 19th day of September, A. D., 1899.

[SEAL.]

WEBSTER DAVIS,
Assistant Secretary of the Interior.

Countersigned:

C. H. DUELL

Commissioner of Patents.
